ELECTROPNEUMATIC ACTION FOR THE OPERATION AND CONTROL OF MUSICAL
INSTRUMENTS

Application filed February 6, 1930, Serial No. 426,359, and in Australia May 21, 1929.

Our invention relates to an improved electropneumatic action for the operation and control of musical instruments, being particularly adapted for use in connection with pipe organs, the object being to provide means whereby the flow of air from the wind chest to the organ pipes or other pneumatic device or motor may be reliably and simply controlled from the manuals or keyboards.

It comprises the provision of a chamber in the lower part of the wind chest and beneath the foot of the pipe of the organ or other instrument, the top of such chamber being formed by a flexible diaphragm adapted to normally seal the pipe of the instrument, the bottom of the chamber having air inlet and air outlet holes the former connecting with a trunking containing air under higher pressure than that within the wind chest, and the latter connecting with the atmosphere. Supported upon the bottom of the chamber is a rocking plate valve the two wings of which are adapted to cover the air inlet hole and the air outlet hole respectively; and fitted to the bottom of the chamber adjacent to the air inlet hole therein is an electro magnet such that when the magnet is energized the valve is rocked to close such air inlet and open the air outlet.

In order that our invention may be the more clearly understood we will describe the same with reference to the accompanying drawings in which:—

Fig. 1 is a central section showing our invention applied to the pipe of an organ, and

Fig. 2 is a plan of the parts below line 2—2 of Fig. 1.

In the drawings we have shown our chamber as formed in the bottom board of the wind chest, that being a simple and convenient manner of forming same, but it may be made as a self-contained unit positioned and secured either within or even outside of the wind chest.

In applying our invention as shown in the drawings we make use of a rocking valve 1 consisting of a plate or disc of soft sheet iron which is bent slightly along its

centre to form two wings as shown. This valve is placed on the upper surface of a horizontal plate 2 so that it may rock through a small angle, being held in place by two pins 3 which project from the plate 2 and pass through perforations in the valve. The rocking valve 1 is faced with leather or other more or less resilient material to facilitate its operation and to make it air tight and silent in action.

The plate 2 is secured to the wind chest 4 below a hole or chamber 5 cut in the bottom board of same, and forms the bottom of such chamber. In its one position of rest (its normal position) the valve covers and seals an air outlet hole 6 in the plate 2, and in its other position of rest it covers and seals an air inlet hole 7 in the plate 2.

The air inlet hole 7 communicates through a tube 8 with a trunking 9 containing air from the bellows or blower at a higher pressure than that within the wind chest, and the outlet hole 6 communicates with the atmosphere.

Near the air inlet hole 7 and on the same side of the axis about which the valve 1 rocks is an electro magnet 10, preferably a horseshoe magnet, the poles of which protrude into and are held in the bottom plate 2.

The top of the chamber 5 is sealed by a flexible diaphragm 12 of leather or other suitable material, which diaphragm seals the chamber 5 from the wind chest 4 and prevents any passage of air from the one to the other.

Immediately above the diaphragm 12 is a tube 13 of fibre or other suitable material one end of which is situated adjacent to the diaphragm and is normally sealed thereby, and the other end of which projects into and is secured in a hole in the upper board of the wind chest 4, which hole forms the seat for the foot of the pipe 14 or instrument to be operated.

The operation of our invention is as follows:

By means of bellows or blower an air pressure sufficient to operate the pipes of the instrument is maintained in the wind chest 4,

and a substantially higher pressure is maintained in the trunking 9. When the parts are in the position shown in full lines in Fig. 1, which is their normal position, the high air pressure in the trunking 9 flows through the tube 8 and inlet hole 9 into the chamber 5 deflecting the diaphragm 12 upward to seal the tube 13 and so prevent any flow of air from the wind chest 4 through the tube 13 to the pipe 14.

When the electromagnet 10 becomes energized by current controlled from the keyboard the rocking valve 1 is deflected to the position shown by long and short dots in Fig. 1 sealing the inlet hole 7 and thereby cutting off the supply of air from the trunking 9 to the chamber 5, and at the same time unsealing the outlet hole 6 and thereby permitting the air pressure in the chamber 5 to fall to atmospheric pressure. This causes the diaphragm 12 to be deflected downward by the pressure in the wind chest 4, such position being shown by long and short dots in Fig. 1. The tube 13 consequently becomes unsealed and air from the wind chest 4 is admitted to the pipe 14. This condition holds while the electric circuit remains closed. When the electromagnet circuit is opened by releasing the key contact the rocking valve 1 reverts to its normal position allowing the higher air pressure from the trunking 9 to fill the chamber 5 and so deflect the diaphragm 12 upwards, sealing the opening to the tube 13 and cutting off the supply of air from the wind chest 4 to the pipe or musical instrument which then ceases to operate.

The same device or mechanism may be used to control the supply of air under pressure to a pneumatic motor of any ordinary type which may be used to operate contacts or other functions where a mechanical force is required. The air tube to the motor then takes the place of the pipe to be played.

What we claim is:

1. An improved electropneumatic action for the operation and control of musical instruments comprising a chamber positioned in the lower part of the wind chest and adjacent to the foot of the pipe of the instrument or of the pneumatic motor of device to be operated, the top of the chamber being formed by a flexible diaphragm adapted to seal a tube communicating with the said pipe, and the bottom of the chamber having air inlet and air outlet holes the former connecting with a trunking containing air under higher pressure than that within the wind chest and the latter connecting with the atmosphere, a rocking plate valve supported upon the bottom of the chamber, and an electromagnet fitted to the bottom of the chamber adjacent to the air inlet hole therein and adapted to be energized from the keyboard or manual so that when the mag-

net is energized the rocking plate valve is rocked to close such air inlet, substantially as described.

2. In an electropneumatic action for the operation and control of musical instruments comprising a wind chest having a chamber in the lower part thereof, a musical instrument mounted in said wind chest and having the horn portion thereof disposed closely adjacent said chamber, a high pressure air conduit carried by said wind chest, a conduit connecting said chamber and said high pressure conduit and forming an air inlet for said chamber, an air outlet formed in said chamber, an angularly formed metallic plate valve rockably supported between said inlet and outlet, a flexible diaphragm sealing the upper portion of said chamber and adapted to be flexed into sealing engagement with the horn of said instrument upon energization of said electro-magnet, and an electromagnet disposed adjacent the air inlet of said chamber, whereby said valve will be rocked to close said inlet and open said outlet of said chamber.

In testimony that we claim the foregoing as our invention we have signed our names this 6th day of January, 1930.
